DISPENSING RECEPTACLE

Bernard G. Klein, Chicago, Ill.

Application January 5, 1935, Serial No. 575

1 Claim. (Cl. 221—16)

This invention relates to dispensing receptacles and, more particularly, to receptacles adapted to dispense their contents in an inverted position and provided with a self-closing outlet.

5 A feature of one embodiment of the invention is that the closure may readily be adjusted to dispense liquids of different viscosity, that is, if the closure is positioned to dispense free-flowing liquids, it may readily be adapted to emit more viscous liquids.

10 A further feature is that the closure is adapted to prevent liquid droplets remaining on the closure valve when the receptacle is righted smearing and congealing on the outer surface of the closure device.

15 An object of the invention is to provide a simple durable dispensing medium that can be manufactured inexpensively and assembled readily.

20 Other features and advantages will appear in the following description in conjunction with the drawings, in which—

Figure 1 is a front elevation of the improved dispensing receptacle; Fig. 2, a plan view; Fig. 3, an enlarged broken vertical sectional view; Fig. 25 4, a vertical sectional view of a modification; Fig. 5, a plan view of a liner employed in the modification of Fig. 4; Fig. 6, a vertical sectional view of another embodiment; Fig. 7, an elevation of a valve nipple; Fig. 8, an elevation of a coil spring; 30 Fig. 9, an elevation of a liner.

35 Referring to the drawings, the reference character 1 designates a receptacle of any desired type adapted to contain a liquid to be dispensed. As here shown, it represents a small glass bottle adapted to contain a lotion. The bottle 1 is provided with a neck 8 to which a cap or top, constructed in accordance with my invention, is adapted to be secured. This neck may have a smooth surface so that the cap or top may fit frictionally thereon, but as shown in Fig. 3 at 9, it is preferably threaded to receive a correspondingly threaded cap or top.

40 The cap 10, preferably fashioned from phenolic condensation material, comprises a frusto-conical upper portion 11 and a cylindrical lower portion 12. The lower portion 12 is shown screw-threaded at 13 to coat with the threaded neck 8 of the receptacle and has a vertical portion 14 extending above the threads. The frusto-conical portion 11 terminates in a centrally located aperture adapted to receive tapered valve means 15. The upper edge 16 of the cap in contact with the valve inclines slightly downwardly and inwardly to form a groove for a purpose to be explained. 45 The skirt 17 formed on the base of the valve 15 is

adapted to bear against a shoulder 18 in the inner part of the apex of the cap. The base of the valve is also provided with a notch 19 to house the upper section of a coil spring 20 adapted to yieldingly hold the skirt of the valve 17 against the shoulder 18 of the cap. The lower convolution of the spring 20 rests on an annular centrally apertured washer or liner 21 disposed on the top of the neck of the receptacle. The spring 20 likewise serves to yieldingly retain the washer 21 on 10 the bottle top to form a seal thereon when the receptacle is inverted.

15 It will be readily understood that to remove the liquid from the container, the container is inverted and by the application of slight pressure on the valve member 15, the valve will be unseated, permitting the flow of the liquid contents from the closure. The removal of pressure on the valve closes the cap and immediately halts the flow of liquid. The provision of the 20 groove 16 on the edge of the closure tends to retain liquid droplets remaining on the edge and to prevent its flow along the outside of the closure.

25 It is also to be understood that the closure described may be adapted to control the flow of liquids of varying viscosities, that is, if the receptacle contains a free flowing perfume and it is desired to substitute a more viscous liquid, it is unnecessary to change the entire closure device since by turning the cap one-half revolution in a counter-clockwise direction, or more, depending on the viscosity of the liquid and the pitch of the screw-threads, the tension on the coil spring is lessened and the annular opening formed by unseating the valve is greater without a substantial increase in the pressure applied to the valve. Conversely, the closure may be adapted for the admission of a less viscous liquid by turning the cap in a clockwise direction to form a smaller annular opening on the application of the same force.

35 A modified closure is shown in Figs. 4 and 5. In that embodiment the screw-threaded cap 30, tapered valve 22 and coil spring 23 are similar 40 to those shown in Figs. 1-3 and 7-9. The lower coil of the spring rests on a liner 24 preferably fashioned from a phenolic condensation product and equipped with threads 25 to engage the threads 26 on the interior of the cap. The liner is preferably provided on its upper surface with an annular groove 27 adapted to receive the lower convolution of the coil spring and it may likewise be equipped with suitable apertures 28 in which the prongs of a forked mem- 50

ber may be inserted to assist the insertion and removal of the liner. An annular thin cork or paper seal 29 may be disposed between the liner and the bottle top to form the seal therebetween in shipping, it being understood that the seal may be readily ruptured when the liquid is to be removed.

A further modification is shown in Fig. 6. In that modification, the screw-threaded cap 40, 10 tapered valve 41, coil spring 42, and centrally apertured liner 43 are similar to those previously described and shown in Figs. 1 to 3. The valve 41, the coil spring 42 and the liner 43 shown in Figs. 7, 8 and 9, respectively, are the same as 15 the members described in Figs. 1 to 5, and may be employed therein, except that the liner 43 differs somewhat from the liner 24 of Figs. 4 and 5. The interior of the closure cap 40 is provided with a centrally located depending ridge 20 or wedge-shaped portion 44. Upon assembling the closure, a portion of the liner 43 adjacent its periphery bears against the ridge portion 44, spreading the periphery slightly to secure a tight fit in the closure and a seal above the liner.

25 While I have shown and described certain em-

bodiments of my invention, it is to be understood that it is capable of many modifications. Changes, therefore, in the construction and arrangement may be made without departing from the spirit and scope of the invention as disclosed in the appended claim, in which it is my intention to claim all novelty inherent in my invention as broadly as permissible, in view of the prior art.

What I claim as new and desire to secure by 10 Letters Patent is:

In an adjustable closure for dispensing receptacles, a hollow closure-cap having a cylindrical portion terminating in a nozzle, a spring-seat member movable vertically within the cylindrical portion of said cap, spring means disposed on said seat member, and a tapered member protruding from said nozzle, normally closing the same by the pressure of said spring and forming an annular opening in said nozzle when 20 pressed inwardly, the size of the opening for a given inward pressure depending on the position of the cap on the receptacle.

BERNARD G. KLEIN. 25
